FLUID HANDLING APPARATUS

Carl R. Houghton, Connersville, Ind., assignor to
Roots-Connersville Blower Corporation, Con-
nersville, Ind., a corporation of Indiana

Application January 12, 1938, Serial No. 184,508

6 Claims. (Cl. 121—70)

This invention relates to fluid handling apparatus and more particularly to gas meters and gas pumps and the like.

One object of the invention is the provision of a fluid handling apparatus, such as gas meter or gas or vacuum pump or the like, in which the material is handled by a plurality of interfitting impellers rotatable in an impeller casing, the arrangement being such that the discharge of material takes place substantially horizontally and in such manner that liquid or heavy material is cleaned from the bottom of the impeller chamber.

Another object of the invention is the provision of a fluid handling apparatus embodying a lower impeller having at least three lobes, intermeshing with an upper impeller, the bottom of the impeller casing extending substantially horizontally to an outlet opening from a point below the axis 20 of rotation of the three-lobe impeller.

Another object of the invention is the provision of an impeller for fluid handling apparatus, the rolling surface of the impeller being formed of a number of separate curved metal plates welded together and to supporting ribs which project from a carrying shaft.

Other objects and advantages of the invention will be apparent from the following description, the appended claims, and the accompanying drawing, in which:

Fig. 1 is a vertical sectional view of a fluid handling apparatus embodying the present invention, taken centrally of an impeller chamber on line 1—1 of Fig. 2;

Fig. 2 is a section on the line 2—2 of Fig. 1; and

Fig. 3 is a section on the line 3—3 of Fig. 1.

Referring more particularly to the drawing by reference numerals, 10 generally designates the casing of a fluid handling apparatus such as a gas meter or gas or vacuum pump or the like, and herein shown as a gas meter which measures or meters the flow of gas by counting mechanism operated by intermeshing impellers 11 and 12 which operate in the impeller chamber 13. The casing preferably comprises end members 15 and 16 and the body member 17, interconnected by bolts or other suitable fastening means so as to provide the impeller chamber 13. At an upper portion of the body member 17, and preferably at a lateral side of the meter is an inlet opening 18 through which the gas is supplied to the impeller chamber 13. At the opposite side of the meter is a horizontally extending outlet opening 19 provided near the bottom of the casing.

The impellers 11 and 12, as herein shown, are lobed intermeshing members having rolling surfaces which interfit one another, these surfaces preferably being involute curves. The lower impeller has more than two lobes, and the upper

impeller may have two or more lobes, the number of lobes of the upper impeller being preferably one less than the number of lobes of the lower impeller. With three lobes or more on the lower impeller, the curved side wall 20 over which the ends of the impeller 12 sweep near the lower portion of the casing may be continued substantially horizontally and tangentially by the bottom wall portion 21 to the outlet opening 19, the latter being arranged at one side of the meter. 10 With such a construction any liquid passing into the meter with the gaseous medium measured will be promptly cleaned at the bottom of the impeller casing, preventing the possibility of an accumulation of liquid in the meter. A liquid 15 accumulation in a meter that has been shut down over an appreciable length of time, especially if the liquid is heavy, or thick, blocks the impeller and prevents its rotation when the gas is turned on, and is quite objectionable, so it has been the 20 practice to arrange the outlet opening of a lobed impeller type of meter so that the discharge takes place in a downward direction from the bottom of the meter, the meter being arranged on supports or piers and the discharge pipe extending downwardly from the center of the meter base between these piers. The arrangement as herein 25 set forth, however, provides a horizontal discharge of the metered fluid while preventing the possibility of an accumulation of a liquid taking place within the meter, since any liquid carried along into the meter by the flow of gas will drain freely from the tip of the impeller and be carried by the impeller tip to a point from which the liquid may flow horizontally to the outlet opening. 30

The impeller 11 is provided on a shaft 23 which is rotatably mounted, preferably by means of antifriction bearings 24 and 25 in the end members 15 and 16 of the casing, similar bearings 26 and 27 supporting the shaft 28 of the impeller 12 which is below the impeller 11. To provide for the proper timed operation of the two impellers, the shafts 23 and 28 are provided with timing gears 30 and 31, intermeshing with one another and operating in the gear chamber 32 at one side of the impeller chamber. One of the shafts 23 or 28 is provided with a suitable counting device 33 indicating or counting the revolutions of the shaft and thus giving an indication of the amount of gas metered. It will be understood that the pressure of the gas supply may be utilized for turning the impellers in the impeller chamber, or the impellers may be positively driven in any suitable manner as desired. 45

The gears 30 and 31 are preferably provided with teeth having quite long addendum with only enough clearance at the bottom of the teeth to allow free passage of a mating tooth. These gears may be of the character described, for ex- 50 55 60

ample, in Wilkin Patent 1,646,373, October 18, 1927.

Each of the impellers 11 and 12 is preferably constructed of metal plates, of steel or the like, integrally connected to one another and to its supporting shaft by welded connections. As shown in Figs. 2 and 3, the impeller 11 is formed of curved metal plates 35, 36, 37 and 38 which define the rolling surface of the impeller, each 10 of these plates forming a part of the waist and one-half of a lobe, the outer ends of the adjacent plates having a welded connection to one another as indicated at 39, and the waist portions of these plates being welded to one another and to the 15 shaft 23 as indicated at 40. The weld lines 39, which extend parallel to the shaft axis where the impeller is straight, and which extend at a helical angle where a spiral impeller is employed, preferably project beyond the ends of the curved 20 plates to form a hard seal member at the tip of the impeller lobes where the impeller sweeps across the curved wall of the impeller chamber. The curved plates 35 to 38 are welded as indicated at 43 to supporting transversely extending 25 rib plates 41 and 42, and the latter are welded at their inner ends, as indicated at 44, to the shaft 23. By constructing the impellers of welded steel plates, instead of making them in the usual manner as metal castings, a very desirable 30 construction is provided, as the impeller may be made of light weight with the rolling surfaces of the impeller, which must be accurately made, formed quite economically and accurately in curved plate sections suitably 35 formed to the required shape, and integrally connected to one another and to the supporting ribs, and welded at the tips of the lobes to provide a hard wear strip extending along the portion of the impeller which engages or sweeps along the 40 curved surface of the impeller chamber.

The impeller 12 is also constructed of curved plate portions 45, each forming a part of the waist and a half of a lobe, the plate portions being welded together as indicated at 46 and 45 welded to radial rib members 48 and to transverse rib plates 49 along their lines of contact. The radial plate members 48 and the rib plates 49 are preferably flat steel plates welded to one another along their lines of contact, and welded to the 50 shaft 28.

While the form of apparatus herein described constitutes a preferred embodiment of the invention, it is to be understood that the invention is not limited to this precise form of apparatus, 55 and that changes may be made therein without departing from the scope of the invention which is defined in the appended claims.

What is claimed is:

1. Fluid handling apparatus of the character 60 described comprising a casing having inlet and outlet openings and providing an impeller chamber, said inlet opening extending substantially horizontally adjacent the top of the casing and said outlet opening extending substantially horizontally adjacent the bottom of the casing, a two-lobed impeller and an impeller having more 65 than two lobes rotatably mounted and intermeshing in said chamber, intermeshing gears interconnecting said impellers for timed operation, said casing having an arcuate wall with a radius of curvature substantially equal to the maximum radius of the impeller which has more than two lobes and having a bottom portion at the bottom of the impeller chamber extending 70 substantially horizontally and substantially tan-

gentially to said arcuate wall from a point below the axis of rotation of said last-named impeller to said outlet opening.

2. Fluid handling apparatus of the character described comprising a casing having inlet and outlet openings, said inlet and outlet openings extending substantially horizontally adjacent the top and bottom respectively of the casing and at opposite sides thereof, a plurality of lobed interfitting impellers rotatably mounted one above the other in said casing, intermeshing gears interconnecting said impellers for timed operation, said casing having a bottom portion extending substantially horizontally to said outlet opening from a point below the axis of rotation of the lower impeller.

3. Fluid handling apparatus of the character described comprising a casing having arcuate walls and having inlet and outlet openings, said outlet opening extending substantially horizontally adjacent the bottom of the casing, a plurality of lobed interfitting impellers rotatably mounted one above the other in said casing, the lower impeller having more than two lobes and operable along one of said arcuate walls, intermeshing gears interconnecting said impellers for timed operation, said casing having a bottom portion extending substantially horizontally to said outlet opening from a point below the axis of rotation of the lower impeller and substantially tangentially to said one arcuate wall.

4. A gas meter comprising a casing having inlet and outlet openings at opposite sides laterally of the casing with the outlet opening arranged adjacent the bottom of the casing, a plurality of lobed impellers rotatably mounted one above the other in said casing, intermeshing gears interconnecting said impellers for timed operation, said casing having a side portion with a radius of curvature substantially equal to the maximum radius of the lower impeller to interfit therewith and having a bottom portion extending horizontally to said outlet opening tangentially to the bottom of said side portion.

5. A gas meter comprising a casing having inlet and outlet openings with the outlet opening at a side thereof adjacent the bottom of the casing, a three-lobed impeller rotatably mounted in the lower portion of said casing, a two-lobed impeller interfitting therewith and rotatably mounted in the upper portion of said casing, intermeshing gears interconnecting said impellers for timed operation, a side of said casing having an arcuate curvature fitting the lower impeller and the lower portion of said casing extending substantially horizontally from said arcuate portion to said outlet opening from a point below the axis of rotation of the three-lobed impeller.

6. Fluid handling apparatus of the character described comprising a casing having inlet and outlet passages extending substantially horizontally at opposite sides of the casing with the outlet passage at the bottom of the casing, a three-lobed impeller rotatably mounted in the lower portion of said casing, a two-lobed impeller interfitting therewith and rotatably mounted in the upper portion of said casing, intermeshing gears interconnecting said impellers for timed operation, a side of said casing having an arcuate curvature fitting the lower impeller and the lower portion of said casing extending substantially horizontally from said arcuate portion to said outlet passage from a point below the axis of rotation of the three-lobed impeller.
